UNITED STATES PATENT OFFICE.

CHARLES W. YERBURY, OF SPRINGFIELD, ILLINOIS.

RAIL-JOINT.

1,033,769.

Specification of Letters Patent. Patented July 23, 1912.

Application filed November 4, 1911. Serial No. 658,497.

To all whom it may concern:

Be it known that I, CHARLES W. YERBURY, a citizen of the United States, and a resident of Springfield, in the county of 5 Sangamon and State of Illinois, have invented a new and Improved Rail-Joint, of which the following is a full, clear, and exact description.

My invention relates generally to a rail 10 joint and more particularly to a fish plate, adapted for use on steam, electric and elevated roads, or in mines or quarries, or in fact in any place where a construction is required to hold rails together for tractive 15 service.

The object of my invention is to provide a new and improved structure specially adapted to holding adjacent ends of meeting rails, the arrangement being such that no 20 bolts or equivalent devices are necessary.

A further object of my invention is to provide a structure of this class, which by reason of the arrangement of the parts is well adapted to hold the meeting ends of 25 adjacent rails in position and insulated from the roadbed, thereby facilitating the operation and maintenance of signal systems, which make use of the rails as parts of the circuit.

30 Further objects and advantages of the invention will appear as description further proceeds, the new and novel results being set forth in the appendant claims.

Reference is to be had to the accompanying drawings, forming a part of this specification, in which similar characters of reference indicate corresponding parts in all the views and in which

Figure 1 is a side view of the preferred 40 form of my invention, operative position; Fig. 2 is a vertical sectional view thereof; Fig. 3 is a side view of the locking devices; Fig. 4 is an end view thereof; Fig. 5 is a vertical sectional view of a modified form 45 of plate; Fig. 6 is a bottom plan view; Fig. 7 is a vertical sectional view of a further modified form of plate; Fig. 8 is a bottom plan view thereof; and Fig. 9 is a sectional view of the locking devices showing a 50 modified means for spreading them.

Referring particularly to Figs. 1 to 4, the adjacent ends of two rails are designated 1 and 2 respectively, the fish plates being indicated at 3 and 4. The plates are preferably 55 of the shape shown in Fig. 2, the lower outer ends of the plates being adapted to be sup-

ported in a suitable tray 5, having shoul- 60 dered sides 6-7, the tray being secured on a tie 8, by any means, such as spikes 9.

An intermediate portion of one side of 65 each of the plates is removed as at 10, whereby pockets are formed, which pockets, when the plates are in the position shown in Fig. 2 are adapted to receive the web and the bottom portion of the meeting ends of 70 the rails. The lower side walls of the pock- 75 ets in the plates form, in effect, shelves on which the bottom portions of the rails rest substantially throughout their width. The lower portion of each of the plates along the bottom side thereof is preferably removed as at 11, whereby the plates rest at their outer edges, providing for a firmer engage- 80 ment of the parts when a train is passing over the rail, since the downward pressure 85 on the top of the rail serves to bring the upper portion of each of the plates into firmer engagement with the rail.

The construction which I have set forth 90 is well adapted to provide for insulation of the rails and to this end I have shown suitable insulating material 12, extending along each side of the web and around the bottom portion thereof, which insures no electrical 95 contact between the rails and the plates.

In order to firmly secure each plate in 100 position on opposite sides of the rails, I pro- 90 vide suitable locking devices, shown partic- 105 ularly in Figs. 3 and 4, to be positioned in the pockets 10, the sides of the plates being provided with openings 13, whereby the locking devices are made accessible. These locking devices are made up of two 110 elements 20-21, the opposite ends of each element being of unequal dimension as shown at 22-23 in Fig. 3. Extending throughout the length of each of the elements 20-21 and along the central portion thereof, are co-operating parts, made up of a wedge 24 on the part 20 and a groove or slot 25 on the element 21; each side of each of the elements is provided with a series of recesses or notches 26, which, when the elements are in operative position, are located as shown in Fig. 3. Since each of the ele- 105 ments is higher at one end than at the other, the combined lengths at each end, however, being equal, they will provide a wedge-like action when a suitable key is inserted in the recesses 26, whereby when the key is turned, the elements will move longitudinally of each other, thereby causing them to firmly

105

110

grip the inside top portion of the plate 3 and the top of the bottom of the rail 2 as shown particularly in Fig. 2.

With the construction thus defined, it is 5 obvious that the tray 5 which is secured to the ties, determines the position of the plates 3 and the plates firmly engage the opposite sides of the rails, holding these rails in position with ample space for expansion and 10 at the same time doing away with the necessity of bolts and providing a joint that will be substantially noiseless.

The construction which I have shown is capable of some modification in various 15 parts and in Figs. 5 and 6, I have shown a joint involving a slight departure. In this case each of the plates 3^a is provided with a pocket or recess 10^a, which pockets receive the elements of the locking devices previously 20 described, the departure residing in the form of the bottom portion of each of the plates. The plates are positioned with respect to each other and are held against movement, by making the bottoms thereof 25 inter-locking, or as shown in Fig. 6. In this construction, each plate is provided with an extension 41 and also with a recess 42 of substantially the same dimensions as the extension and adapted to be received there- 30 by, all of which is shown in this figure. By reason of such construction and inter-engagement of the parts, the two plates are held rigidly with respect to each other and the engagement with the rail is insured.

35 In Figs. 7 and 8, I have shown a further modification. In this instance the plates 3^b have a continuous bearing surface for the rail as shown in Fig. 7, the departure residing in the fact that the interior of the 40 pockets 10^b is such that the whole width of the bottom of the rail is in engagement with the bottom of the plates, whereby a construction is afforded which may be better adapted for certain classes of heavy traffic. 45 In order to insure that the plates 3^b will be inter-locking and held in close relation with each other, as well as with the rail itself, the bottom of each plate may be provided with a plurality of projections 41^b, adapted to 50 engage in similarly formed recesses 41^c, whereby the inter-engagement of the recesses and the projections will accurately determine the position of the plates.

Instead of using the particular form of 55 locking elements shown in Fig. 3, a modified construction thereof which is shown particularly in Fig. 9 may be utilized. In this instance the purpose of the locking elements is the same as that previously set forth, namely to cause a firm engagement 60 between the inside of each pocket and the bottom of the rails, which engagement is brought about by the binding of the locking elements between these parts. In Fig. 9, the 65 locking elements 50—51, are each provided

with tapered, threaded recesses 52—53, the outer ends of each of which communicate with suitable recesses 54. A tapered locking screw 55 having a squared outer end 56 adapted for engagement with a suitable wrench or key is positioned in each pair of recesses, the engagement of the key with the outer end of each screw and the turning thereof, bringing the screw farther into each pair of recesses, thereby causing the elements 50—51 to be moved apart and into firm frictional engagement with the inside of the plate and the bottom of the rail.

From the above description taken in connection with the accompanying drawings, it 80 will be clear that I have set forth a structure well adapted to perform the functions set forth, the size and shape of the several parts being largely a matter of design, these features being capable of change in order to 85 adapt the construction to different localities and uses.

Having thus described my invention, I 90 claim as new, and desire to secure by Letters Patent:—

1. A construction of the class described embodying a plurality of plates adapted to be positioned on opposite sides of the meeting ends of rails, means for securing the plates in position on a tie, together with a 95 plurality of longitudinally slidable locking means engaging the plates and the rail for holding the parts together, the locking means being positioned on opposite sides of the rail.

2. A construction of the class described comprising a plurality of plates having openings in the sides thereof adapted to be positioned adjacent the meeting ends of rails, means for holding the plates in position on a tie, and slidable locking means positioned adjacent each plate and one side of the rail for holding the parts together, the said opening affording the entrance for a suitable key in the operation of the said means.

3. A construction of the class described comprising a plurality of plates having pockets in one side thereof, the said plates being adapted to be positioned adjacent the meeting ends of rails and on opposite sides thereof, means for securing the plates to a tie or other support, together with a plurality of locking means positioned within the pockets and engaging each plate and the sides of the rail whereby the parts are held together.

4. A construction of the class described comprising a plurality of plates, each plate having a pocket in one side thereof, the plates being adapted to be positioned on opposite sides of the meeting ends of rails, means for securing the plates on a tie or other support, together with a plurality of longitudinally slidable locking means positioned in the pockets and engaging one side

of the pockets and opposite sides of the rail whereby the plates are held in frictional engagement with the rail.

5. A construction of the class described comprising a plurality of plates, each plate having a pocket in one side thereof, an opening in the side of each plate communicating with the pocket, the plates being adapted to be positioned on opposite sides of the meeting ends of adjacent rails, a locking device made up of two elements movable longitudinally with respect to each other, a locking device being positioned in each of the said pockets, each locking device being operable 10 by means of a key or wrench inserted into engagement therewith through the said openings in the sides of the plates, the elements of the said device engaging the side wall of the pocket and one side of the rail 15 whereby the parts are frictionally held together.

6. A construction of the class described comprising a plurality of plates having pockets therein, the pockets being intermediate the top and bottom of the plates, the 25 plates being adapted to be positioned on opposite sides of the meeting ends of rails, together with a locking device positioned in each pocket, each device being made up of two elements movable longitudinally with 30 respect to each other, the said elements in locked position engaging a side wall of each pocket and one side of the rail, thereby holding the parts together by frictional contact.

In testimony whereof I have signed my 35 name to this specification in the presence of two subscribing witnesses.
